H. A. CUMFER

SHINGLE CUTTING MACHINE

Filed August 7, 1924

Inventor:
HARRY A. CUMFER
Tonee Rain
Atty.

UNITED STATES PATENT OFFICE.

HARRY A. CUMFER, OF CHICAGO, ILLINOIS, ASSIGNOR TO GUYTON & CUMFER MFG. CO., OF CHICAGO, ILLINOIS, A CORPORATION OF ILLINOIS.

SHINGLE-CUTTING MACHINE.

Application filed August 7, 1924. Serial No. 730,634.

To all whom it may concern:

Be it known that I, HARRY A. CUMFER, a citizen of the United States, residing at Chicago, in the county of Cook and State 5 of Illinois, have invented certain new and useful Improvements in Shingle-Cutting Machines, of which the following is a specification.

This invention relates to improvements 10 in shingle cutting machines.

One of the objects of the invention is to provide a machine for alternatively cutting shingle simulating strips and shingles of various and divers forms from a progressively movable sheet of composition roofing 15 material.

Another object of the invention is to provide an improved cutter in which the members are removable and which is adapted 20 for severing shingles and shingle simulating strips from a movable sheet of roofing composition.

Another object is to provide a machine in which the fixed and rotatable cutters are 25 each removable, whereby other cutters may be substituted to produce shingles and shingle strips of many varied shapes.

Another object is the provision of a machine having two types of relatively adjustable, rotatable knives, or cutters, for cutting shingles from a sheet and removing 30 the waste, respectively.

Another object is to provide adjustable and removable cutter-blades having a plurality of cutting edges so that the cutters or knives may be removed and replaced with the selected edge for operation.

A further object is to provide a series of stationary cutters relatively adjustable toward and from cooperating rotatable cutters.

Another object is to provide a machine which will readily sever the waste strips, which are left at the marginal edges of the 45 shingles, or shingle simulating strips, from the sheet without the necessity for maintaining said sheet and marginal strips in substantially horizontal planes during the cutting operation.

Another object of the invention is to provide a machine which may be adjusted to cut either shingle simulating strips or shingles of various forms from a sheet by merely rearranging the cutters or knives and with-

out the necessity of first splitting the sheet 55 and then cutting the shingles therefrom.

Another object is, generally, to improve machines of this character.

Other, further and more specific objects and advantages of the invention will be 60 become readily apparent, to persons skilled in the art, from a consideration of the following description when taken in conjunction with the drawings, wherein;

Fig. 1 is a plan view of the structure 65 shown in Fig. 2.

Fig. 2 is a section taken on line 2—2 of Fig. 1.

Fig. 3 is a plan view of the sheet from which a shingle simulating strip, shown in 70 Fig. 4, has been cut, and before the tongues or marginal strips have been severed.

Fig. 4 is a plan view of the finished shingle simulating strip.

Fig. 5 is a view of the end of the sheet, 75 similar to Fig. 3, from which three shingles have been cut and from which two shingles are projecting to be cut by the second knife or cutter in a revolution of the knife arbor.

In all the views the same reference characters are employed to indicate similar 80 parts.

The cutting instrumentalities of my machine are mounted upon a suitable support, shown in this case to be a table 10 and side 85 members 11, the latter supporting a rotatable arbor or shaft 12 which has bearing on said frame. The arbor 12 may be rotated by any suitable means, such as a gear wheel 13 or other suitable power transmitting instrumentality.

The adjustable and removable cutters are supported upon the table 10, preferably upon the horizontal wall 14, and consists, as illustrated in Figs. 1 and 2, in a series of 95 parallel cutters 15, suitably spaced apart to leave a space therebetween substantially equal to the width of the shingles. The upper wall 16, of the table, may be slotted at intervals to provide openings within 100 which the cutters 15 are inserted and secured by screws 17, or otherwise, to the table 10. These cutters are more securely held in place by the overlying plate 15', which is clamped upon the top edges of the 105 cutters by bolts 16'.

Between the cutters 15 and located transversely of the longest axis of the cutter is

a double edge knife or cutter 18, secured to the wall 19 of the table 10 by cap screws 20, and resting on a ledge or shoulder 21 immediately above the apron 22. Each of the cutters 18 and a pair of cutters 15 cut three sides of a rectangle. The cutters 18 are adjustable by use of shims 18' of varying thicknesses to be placed behind them.

Secured to the arbor 12, by feathers or keys 23, are a series of spaced apart arms 24, each carrying separable double edge reversible cutters 25. The side edges of the cutters 25 cooperate with the sides of the members 15 and the ends 26 of the cutters 25 cooperate with the cutters 18; while the cutters 18 and 26 cut the ends of the shingles, leaving strips 27, shown more clearly in Fig. 3, between the shingles cut from the sheet. Located between the arms 24 are other smaller and shorter arms 28 that are rotatably adjustable on the shaft or arbor and secured in adjusted positions by set screws 29. The arms 28 jointly carry a double edge removable cutter or blade 30, secured thereto by cap screws 31, which equals in length the combined length of the cutters 25. The arms 28 are located on the shaft or arbor 12 in angular relation to the arm 24, so that the cutter 30 will act subsequently to the operation of the cutters 25.

The cutters 25 cut the sheet 32 in cooperation with the cutters 15 along the edges 33 or sides of a rectangle, and in cooperation with cutters 18 along the edges 34 or one end of a rectangle, thus producing shingle-like parts 35, secured to a continuous part 36 of the shingle simulating strips 37 with slots 38 between the adjoining shingle-like parts 35, from which the tongues or strips 27, shown in Fig. 3, have been cut.

The knife 30, joining the arms 28, then severs the tongues 27 from the sheet leaving a straight edge 39 extending transversely of the sheet 32, after which the sheet is moved forward, by any suitable means, by the time the arms 24 have been rotated, so that the knives 25 and the knife 30 will repeat the operation described.

50 In the modification for cutting separated shingles shown in Fig. 5, the knives 25 have severed the shingles from the notches 40 leaving intermediate shingle-like projections 41 to be subsequently severed at the edge 42 by the knife 30, so that the shingles cut from the notches 40 and the shingles 41 are removed jointly from the sheet 32 by the knives 25 and 30. The tongues or strips 27 at the marginal edges of the shingles 40 are also removed by the knife 30, operating subsequently to the operation of the knives or cutters 25.

From the foregoing description it will be manifest that the angular relation of the arms 24 and 28 may be varied by rotating

them respectively about the arbor 12 and fixing the arms 28 in adjusted position by the set screws 29.

By adjusting the relation of the knives 25 so as to provide a wide space equal to 70 the width of the shingles between adjacent shingles, as in the structure shown in Fig. 5, a plurality of separated shingles may rapidly be severed from the sheet by making the knives 15, that are supported upon the 75 knives 15, that are supported upon the frame 10.

While I have herein shown a single embodiment of my invention for the purpose of clear disclosure, it will be manifest, to 80 persons skilled in the art, that many changes may be made in the general arrangement and configuration of the parts, within the scope of the appended claims.

Having described my invention what I 85 claim as new and desire to secure by Letters Patent, is:—

1. A sheet cutting machine having a series of fixed, separable, independently removable, spaced-apart cutters and parallel intermediate cutters extending therebeyond to provide cutting edges on three sides of a rectangle, over which a sheet is to be fed, in combination with a plurality of spaced apart, complementary, independently removable rotatable cutters having cutting edges on three sides of a rectangle and another rotatable cutter equal in length to the combined width of the series of rotatable cutters aforesaid and means to rotate the 103 rotatable cutters.

2. A sheet cutting machine having a series of fixed, separable, independently removable spaced-apart cutters and parallel intermediate cutters extending therebeyond to 105 provide cutting edges on three sides of a rectangle, over which a sheet is to be fed, in combination with a plurality of spaced apart, complementary, independently removable rotatable cutters having cutting edges on three sides of a rectangle and a rotatable cutter equal to the combined length of the rectangular cutters; means to adjust the angular position of the two types of cutters on a common axis, and means to 115 rotate the said rotatable cutters.

3. A shingle cutting machine having in combination a plurality of fixed, independently removable, spaced-apart parallel cutters with intermediate spaces therebetween, 120 each space equal to the width of the shingle, to cut the side edges of a shingle, and cutters transversely arranged between each pair of parallel cutters to sever the ends of shingles; a rotary member having a plurality of independently removable cutters for cooperation with the fixed cutters and another rotary cutter cooperating with the other cutters to sever the parts left on the sheet by the first mentioned rotary cutters. 130

4. A sheet cutting machine comprising a table having a shoulder formed thereon, a plurality of independently removable, transversely extending cutters supported on said shoulder, a plurality of independently removable, longitudinally extending cutters carried by the table and projecting beyond the faces of the transversely extending cutters, and a movable cutter adapted to operate between the longitudinally extending cutters. 10
5. A sheet cutting machine comprising a table having a transversely extending shoulder formed thereon and longitudinally extending recesses therein, transversely extending spaced, independently removable cutters carried on the shoulder, longitudinally extending independently removable cutters received in the recesses and between 15 the ends of the transversely extending cutters and extending beyond the faces thereof, and a movable cutter adapted to operate between the longitudinally extending cutters.
6. A sheet cutting machine comprising a table having a transversely extending shoulder formed thereon and longitudinally extending recesses therein, a plurality of independently removable transversely extending spaced cutters carried on the shoulder 20 and detachably connected to the table, a plurality of independently removable, longitudinally extending cutters received in the
- recesses between the ends of the transversely extending cutters and extending beyond the faces thereof, means for detachably connecting the longitudinally extending cutters to the table, and a movable cutter adapted to operate between the longitudinally extending cutters. 35
7. A sheet cutting machine comprising a table having a plurality of parallel vertical slots therein; cutting blades longitudinally adjustable in said slots; supports for said blades; a plate overlying said blades; bolts extending thru said plate, and table, to 40 clamp the longitudinal blades firmly in their respective slots; removable, transverse cutting blades between the first mentioned longitudinal cutting blades adjustable longitudinally thereof and cooperating movable 45 cutters to cut three sides from a sheet.
8. A shingle cutting machine having in combination with a plurality of adjustable removable, relatively stationary cutters, of a plurality of adjustable, cooperating, removable and rotatable cutters to cut shingle members from a sheet; a shaft to rotate said rotatable cutters and another cutter on the shaft rotatably adjustable on said shaft with 50 respect to the first mentioned cutters to cut 55 a different part of the sheet.

In testimony whereof I hereunto set my hand.

HARRY A. CUMFER.
